UNITED STATES PATENT OFFICE.

LEWIS AUGUSTUS ASPINWALL, OF JACKSON, MICHIGAN.

NONSWARMING BEEHIVE.

1,410,444.

Specification of Letters Patent. Patented Mar. 21, 1922.

Application filed January 15, 1921. Serial No. 437,442.

To all whom it may concern:

Be it known that I, LEWIS AUGUSTUS ASPINWALL, a citizen of the United States, residing at Jackson, in the county of Jackson and 5 State of Michigan, have invented an Improvement in Nonswarming Beehives, of which the following is a specification.

This invention relates to the controlling of swarming to such an extent that absolute prevention is accomplished. As will 10 be seen, it is radically different from my previous inventions in this line, which gave very good control, but under some circumstances of an intense honey flow, swarms 15 would occasionally issue.

In my previous inventions, slatted frames were used to afford increased room for the bees as the colony becomes crowded, and was 20 a great advance towards the perfect control of swarming. This construction of slatted frames as used in my most successful attempts towards the perfect control of 25 swarming is embodied in the following patents: No. 891,583, patented June 23, 1908; No. 891,584, patented June 23, 1908, and No. 1,198,811, patented September 19, 1916. This latter patent relates to my invention of an auxiliary compartment in connection with the slatted frames. By making one of these 30 compartments queenless and compelling a circuit of bees through the hive proper was the first step resulting in a near approach to success in the perfect control of swarming, and this principle is embodied in my invention hereinafter described.

In my present invention, however, a new principle is also involved, viz., to control the action of the colony in reference to swarming by queenless bees which are kept in a separate compartment known as the controller, 40 in combination with a controller board at the top and rear, so as to leave room for the supers in front and also on top of the hive.

It is to be noted in this connection that 45 with a side compartment made queenless, the bees refuse to store honey above or at the side of the colony. After modifying this construction for two seasons, that is two years, the storage of honey was little or 50 none. Evidently the wire cloth division board allowed the odor of the queenless compartment to permeate the colony proper, thus destroying its energy. But, with the wire cloth above, a converse condition is obtained; 55 instead of the odor of the queenless bees per-

meating the colony proper, the ascending warmth carries the queen odor above vitalizing the queenless bees in the controller so they do not realize their queenless condition, while the normal vigor of the colony proper 60 is maintained.

It is a well known fact that queenless bees do not swarm for the reason that no swarms can issue without a queen and no colonies swarm unless the bees act as a unit—there 65 must be concerted action on the part of all the bees in a colony. By my present arrangement with the use of the controller above separated from the main hive by a controlling board, which affords a rear entrance, thereby giving two entrances instead of one, the manner of working is such 70 that the bees with a few combs of brood placed in the controller during any period the hive becomes populous, and made queenless 75 thwarts the tendency to prepare for swarming.

The queen is left below and three or four empty combs are substituted to take the place of those with brood, preferably sealed brood which are placed in the controller. The controlling board consists of a space three-eighths to seven-eighths inches wide with queen excluding zinc below, wire cloth above and a plurality of bee escapes whereby 85 the bees in the controller are constantly reinforced by both young and old bees, and in making their flight the young bees return to the controller entrance, not knowing or having marked the old one, while the old bees 90 return as usual, carrying with them the influence of the queenless bees in the controller.

In the drawing:

Figure 1 is a front elevation of my improved hive with device for preventing 95 swarming.

Fig. 2 is the side elevation.

Fig. 3 is a plan view of the controller board, looking from above, also showing a sectional view in the center, and 100

Fig. 4 is a plan view, looking from below or the underside, showing the queen excluding zinc at the bottom, and the bee escapes.

Figure 1 shows the hive with 11 frames 105 wedged together as in my previous invention, without the slatted frames. This enables a hive of shorter construction. Above, supers are placed crosswise of the frames, (which is not common in arranging 110

them), two are shown and the controller at the rear, which shows merely the ends, the frames of which are also placed cross-wise. This is an advantage gained over my 5 previous invention inasmuch as it may be used in connection with any commercial hive.

The hive when placed in position is supported by the steel shoes resting on the 10 ground. The steel U shaped pieces are indicated at 1. 2 represents front bars which support the frame. 3 represents the lower bars which constitute supports for the bottom board. 4 represents the several brood 15 frames. 5 represents button clamps on the follow-board. 6 represents the alighting board. 7 represents the closing pieces held by the buttons. 5' represents the follow-boards. 8 represents the controller and 9 the supers. 10 is a cover protecting the supers from rain and storm. 11 is a cover 20 protecting the controller. 12 represents the clamps holding the super sides to the section holders 13. 14 represents a narrow board 25 in front of the supers which may be moved forward sufficiently to increase the width of the supers. 15 is the lower end of the frame in the controller. A wedge is shown in Fig. 2 and also a locker bar and the follow- 30 board.

By referring to Fig. 3 it will be seen that the controller board is provided with wire cloth on the upper side, which allows the warmth and queen odor of the colony to 35 pass upward and prevents the queenless bees from deserting the hive, which they would otherwise do after the removal of the queen cells, as hereinafter mentioned.

The lower side of the controller board as 40 shown in Fig. 4 is covered by queen excluding zinc which gives the bees an opportunity to pass through into the space where entrance is provided through the bee escapes. 16 represents parts which form a 45 cleated framework for separating the queen excluding zinc and wire cloth and also to contain the bee escapes.

At the rear end of 17 is a thin board about $\frac{3}{8}$ or $\frac{1}{2}$ " in thickness, which forms an alighting board. 18 shows an incline on the side of piece 16, joining board 17, which constitutes an entranceway into the controller. 19 represents the wire cloth screen and 20 the queen excluding zinc. 21 represents the 50 bee escapes, one of which shows the bottom removed and the springs through which the bees pass into the opening above which is shown at 22 in top elevation. 23 represents stops on the controller board and 60 when placed upon the hive rest against the rear end and determine the position of the controller. A couple of screws located near the front of side pieces hold the controller board in position.

65 By removing three or four combs of brood

with bees, as heretofore stated, to the controller, the queen being left below and empty combs substituted, all disposition to swarm is prevented for a time by the loss of brood. With no queen in the controller, 70 queen cells will be constructed over some of the eggs and larvae to rear a queen. These should be removed in about ten days, leaving the controller with bees queenless but they will not desert by reason of the queen 75 odor from below.

As already stated, these queenless bees are constantly reinforced by those from below, both young and old, through the bee 80 escapes—the old ones returning to the former entrance and so carrying the influence of a queenless colony into the colony proper.

The queenless bees being constantly reinforced by young bees from below, or hive proper, through the bee-escapes, are maintained in their strength throughout the season of honey gathering, except when all storage room is shut off, or an insufficient number of supers are used, so compelling the bees to deposit their honey below to the exclusion of brood rearing, thus reducing the number of young bees for reinforcing those in the controller; in which event the controller will eventually become depopulated, 90 and the colony left with an insufficient number of bees for successful wintering.

Under the condition of a loss of brood in the colony proper, no queen cells are started, hence there is no tendency whatever to prepare for swarming. With empty combs substituted for those placed in the controller, egg laying is resumed and the cells are soon filled with brood. As the honey season approaches, supers are placed above at the beginning of clover bloom at which time they 105 enter and store honey with great rapidity. The queenless bees instead of storing honey in the controller combs, pass it down through the wire cloth from mouth to mouth and store it in the supers above the 110 colony proper. This at first was not noticed but finding in the midst of the honey flow no increase of honey in the controller combs, it was discovered by careful watching they were passing the honey down. 115 This adds very much to the storage and yield of honey through the perfect control of swarming.

So perfect is the work and influence through the operation of queenless bees that 120 even with supers left off no swarming will take place. This so changes the action of the colony that an abundance of room becomes unnecessary with my present system. The object of control being to secure 125 the greatest amount of honey, supers are used and tiered to the utmost extent so that the storage of honey by the colony is often two hundred sections per colony during the period of honey flow.

The device working so perfectly leaves nothing to be done during the entire season from apple bloom until autumn except to put on supers and remove them as fast as 5 filled, thus simplifying bee culture and avoiding all the anxiety and annoyance of swarming, which usually comes at a time when supers are to be placed upon the hives and necessitates their removal, because the 10 colony being depopulated by swarming is not in any condition for further storage of honey.

Another advantage which is due to queenless condition in the controller and the bees 15 permeating the colony proper is that the temper or disposition of the bees is modified or changed, making them considerably more docile. Still further, I find although the bees store a greater quantity of honey, there 20 is always ample left in the body of the hive proper for wintering the colony. With the old method the combs are left almost destitute of honey and feeding becomes necessary to supply the colony with winter stores.

25 The whole tendency of the perfect control as herein shown is to lessen the labor in bee culture and to obtain an increased yield of honey, at the same time leaving an abundant supply for wintering the colony, also 30 controlling the disposition of the bees.

I claim as my invention:

1. In a beehive, a main compartment, a controller compartment placed above the main compartment and having an entrance 35 and exit independent of that of the main compartment, and a controller board placed horizontally between the said compartments to permit the passage of bees, except the queen bee and drones, from the main to the

controller compartment and not in other direction. 40

2. In a beehive, a main compartment, a queenless controller compartment placed above the main compartment at the rear thereof and having an entrance and exit independent of that of the main compartment, 45 and a controller board removably placed between the said main and controller compartments to permit the passage of bees, except the queen bee and drones, from the main to 50 the controller compartment and not in other direction.

3. In a beehive, a main compartment, a controller compartment placed above the main compartment and having an exit and 55 entrance independent of that of the main compartment, and devices including an upper mesh member and a lower queen excluding zinc member with intermediate means for permitting the worker bees to 60 pass from the main to the controller compartments and preventing their passage in the opposite direction.

4. In a beehive, a main compartment, a controller compartment placed above the 65 main compartment and having an exit and entrance independent of that of the main compartment, a controller board removably placed between the said compartments and including an upper mesh member, a lower 70 queen excluding zinc member, and a plurality of bee escapes placed intermediate of the mesh member and the queen bee excluder zinc.

Signed by me this 7th day of January, 75
1921.

LEWIS AUGUSTUS ASPINWALL.
